UNITED STATES PATENT OFFICE.

JOHN A. JACKSON, OF CHICAGO, ILLINOIS.

TANK-CAR CONSTRUCTION.

1,082,269.

Specification of Letters Patent. Patented Dec. 23, 1913.

Application filed January 20, 1911. Serial No. 603,721.

To all whom it may concern:

Be it known that I, JOHN A. JACKSON, a citizen of the United States, and a resident of Chicago, in the State of Illinois, 5 have invented certain new and useful Improvements in Tank-Car Construction, of which the following is a specification.

My present invention relates to railway cars in general, and more particularly to 10 cars for carrying a load movable relatively to the car underframing, and has special reference to cars for carrying large quantities of fluids, commonly termed "tank cars."

The principal objects of my present invention are the provision of an improved support 15 for the ends of the body or tank; the provision of improved yieldingly resistant abutments for adequately holding the tank in place and at the same time compensating for 20 the hammer-like blows of the liquid in starting and stopping the car, to the end that the tank may neither become loosened from the framing, nor the framing itself disturbed by the blows of the tank; to provide means 25 whereby the springs, frictional members, or other shock-absorbing and yielding resistant members of the draft gear rigging may be utilized and further proportionally compensate for the movement of the tank; to provide an improved means for mounting 30 the tank relatively to the framing to the end that it may be most readily removed therefrom, together with such other objects as may hereinafter appear.

In attaining the foregoing objects as well 35 as certain further benefits and advantages to be below disclosed I have provided a construction, one embodiment of which is illustrated in the accompanying drawing, 40 wherein—

Figure 1 is an elevational view of a tank car embodying my improvements; Fig. 2 is a sectional view taken on the line II—II of Fig. 1; Figs. 3 and 4 are respectively sectional views taken on the lines III—III and 45 IV—IV of Fig. 2, certain portions being removed.

Referring first more particularly to Figs. 1 and 2, it will be observed that I have here 50 illustrated somewhat diagrammatically a tank car construction comprising longitudinal sill members 10 and 11 supporting a tank 12, the sills 10 and 11 being spaced apart to receive a draft gear rigging, one 55 form of which is indicated in Figs. 3 and 4 to be more fully described hereinbelow.

To provide means of engagement between the tank 12 and the draft gear rigging I have made use of a pair of substantially parallel plates 14 and 15 flanged and riveted 60 to the tank as indicated at 16 and 17, a channel 18 being likewise interposed therebetween, riveted thereto and to the tank as a stiffening member, and for the purpose of further stiffening the engaging members 65 and preventing relative displacement thereof, I make use of a plate 19 and angles 20 and 21, such angles being preferably releasably attached to the members 14 and 15, as well as to the plate 19, to the end that 70 the tank may be readily demounted from engagement with the draft gear for replacement or repair of either as circumstances may require.

Referring now more particularly to Figs. 75 3 and 4, it will be observed that I have here shown my improvements applied for use in connection with a draft gear of the well known Cardwell type, wherein a draw bar 22 carrying a coupler head 23 has rigidly 80 connected thereto a yoke 24 within which are mounted front and rear followers 25 and 26 respectively carrying wedge blocks 27 and 28 working against corresponding wedge blocks 29—29, 30—30 and 31—31, 85 slidably mounted on a transversely disposed member 31^a at the outer end of which are carriage springs 32 and 33 secured thereupon as indicated at 34, a transverse key block 35 passing through slots 36 and 37 90 in the members 10 and 11 acting as a rear abutment to transmit strains to the sills 10 and 11 when the yoke 24 has reached the limit of its rear movement.

As will be manifest upon inspection of 95 Fig. 4, the members 14 and 15 are cut away as indicated at 40 forming bifurcated portions, in order that as the tank is brought into proper position relatively to the draft gear rigging, such members will engage the 100 follower blocks 25 and 26, and that the members 14 and 15 are likewise slotted as indicated at 41 and 42 for the passage of the key block 35, to the end that their movement may not be impeded by such block 105 whether the action on the device takes place through the follower block 25 or the follower block 26.

It is to be understood that the device at the opposite end of the car to that here 110 specifically illustrated is symmetrical with that here illustrated and that broadly con-

sidered I have shown the application of my improvements to a draft gear rigging of the Cardwell type principally for the purpose of convenience, since it is likewise applicable to many other types of draft gear rigging.

The operation of my invention is as follows: Assuming a movement of the liquid in the tank 12 tending to move such tank 10 relatively to the framing 10 in the direction indicated by the arrows in Fig. 1 such movement will be transmitted through the members 14 and 15 to the follower 26 and limited by the action of the wedge blocks 28 against the blocks 29, 30 and 31, and by the resistance of the springs 32 and 33, to the movement of the blocks 30 and 29, with a similar action at the opposite end of the car, but should the movement of the liquid be in a direction contrary to that indicated by the arrows in Fig. 1, such strain would be transmitted to the follower 25 and thence through the wedge blocks 27, 29, 30 and 31 to the springs 32 and 33.

Since there is no movement between the followers 25 and 26 which will cause them to move apart farther than is indicated in Fig. 3 of the drawings, the application of the tank engaging means does not disturb or in any wise interfere with the action of the draft gear rigging in absorbing and transmitting pulling and buffing strains in the customary manner.

It is thought that the operation of constructions embodying my invention will be understood by those skilled in the art to which it pertains without further or particularized description.

Having thus described my invention and illustrated its use, what I claim as new and desire to secure by Letters Patent is the following:

1. In a car construction, in combination, a framing, a body slidably movable relatively to the framing, a plurality of yielding resistances one carried by the framing at each end thereof, and means carried by the body and engaging said yielding resistances, each of said yielding resistances, and said engaging means being adapted for restraining both forward and rearward movement of said body.

2. In a car construction, in combination, a framing, a body slidably supported by the framing, a yielding resistance at each end of the framing interposed between the body and the framing, and engaging means between the body and the yielding resistance, each of said yielding resistances and said engaging means being adapted for restraining both forward and rearward movement of said body.

3. In a car construction, in combination with a framing, a body supported by the framing, and a draft gear rigging comprising a yoke, front and rear followers carried by said yoke, and a yieldingly resistant device interposed between said followers, of means carried by said body and engaging said followers, whereby shocks sustained by said body are absorbed by said yieldingly resistant device.

4. In a car construction, in combination with a framing, a body supported by the framing, and a draft gear rigging comprising a yoke, front and rear followers carried by said yoke, and a yieldingly resistant device interposed between said followers, of a pair of oppositely disposed plates bifurcated for engagement with said followers, whereby shocks sustained by said body are absorbed by said yieldingly resistant device.

5. In a car construction, in combination with a framing, a body supported by the framing, and a draft gear rigging comprising a yoke, front and rear followers carried by said yoke, and a yieldingly resistant device interposed between said followers, of a pair of oppositely disposed plates carried by the body and bifurcated for engagement with said followers, and means for connecting said plates, whereby shocks sustained by said body are absorbed by said yieldingly resistant device and said body is restrained from vertical movement relatively to said draft gear rigging.

In testimony whereof I have hereunto signed my name in the presence of the two subscribed witnesses.

JOHN A. JACKSON.
